UNITED STATES PATENT OFFICE

WILLIAM L. MUELLER, OF LA GRANGE, ILLINOIS, ASSIGNOR TO THE PETERSEN OVEN COMPANY, OF CHICAGO, ILLINOIS, A CORPORATION OF ILLINOIS

TRAY FOR TRAVELER OVENS

Application filed October 4, 1930. Serial No. 486,335.

My present invention relates to traveler ovens and has more particular reference to the construction of the trays that are used in conveying the bakery products through an oven of this character.

The structure which I have devised is assembled so as to insulate the soapstone slab or shelf which forms the sectional hearth from its supporting element which is usually 10 of metal. The parts are assembled in a manner to permit expansion or contraction of the metal without affecting the soapstone slab or shelf. The manner of assembling the parts and of securing the slab to the metal base or 15 support is such that the securing means may be readily accessible to the operator or repairman, at such times as is necessary. The metal structure also provides a substantial protection to the longitudinal edges of the 20 soapstone slab and prevents damage thereto.

Among the objects of my invention are the provision of a shelf or tray for traveler ovens that is novel in construction, dependable in operation, effective in performing the functions 25 for which it is designed, and is economical to manufacture.

I prefer to carry out my invention and to thereby accomplish the several objects thereof in substantially the manner hereinafter 30 fully described and as more particularly pointed out in the claims. Reference will now be made to the accompanying drawings that form a part of this specification, in which,

Fig. 1 is a transverse section of one of the conveyor shelves or trays of a traveler oven made in accordance with my invention.

Fig. 2 is an end elevation showing on a reduced scale two of the trays or shelves in the position assumed in passing around a sprocket and disclosing the accessibility of the securing members.

Figs. 3 and 4 are a transverse section and a plan of a tray slightly modified.

The drawings it will be understood, are more or less schematic for the purpose of disclosing typical or preferred embodiments of my invention, and in these drawings similar 50 reference characters have been employed to

designate like parts wherever they appear throughout the several views.

Referring to the drawings, it will be seen that the tray structure comprises a base or support that has lateral flanges and the soapstone 55 shelf or slab is secured to these flanges by retaining clips or strips that also act as a protection for the edges of the slab.

The supporting base comprises an elongated metal channel of inverted U-shape and it may be either the integral rolled type of channel shown in Figs. 1 and 2 or of the built-up composite type shown in Figs. 3 and 4. In the type shown in Figs. 1 and 2 the web 60 of the channel is disposed in a horizontal plane and the longitudinal flanges 6 thereof project downwardly. The channel piece is of such length that it extends from side to side across the oven and the ends thereof are secured to suitable rollers that travel upon 65 a guide-track on the side-walls of the oven during the movement of the traveler through the 70 chambers of the oven.

The supporting base is provided with flanges that extend laterally from its upper longitudinal edges, said flanges being preferably in the form of angle pieces having vertical flanges 7 that are riveted to the flanges 6 of the base. This arrangement disposes the lateral flanges 8 of the angle pieces in a horizontal plane so that they project outwardly from the vertical plane of the base flanges 6 in the manner shown in Fig. 1. It 75 will be noted the lateral flanges 8 are disposed in a plane slightly above the plane of 80 the upper surface of the web 5 of the supporting base or channel. For the purpose 85 of insulating the shelf from the flanges 8, I place asbestos strips 9 upon said flanges 8 so that the soapstone slab 10 is supported along 90 its longitudinal edges upon the asbestos strips and is heat insulated from the flanges 8 by the strips 9.

A retainer and protecting strip is placed along each longitudinal edge of the soapstone slab or shelf 10, and these strips consist of elongated pieces of sheet metal bent substantially U-shaped in section. The web portion 11 of the retainer and protector is 95 vertically disposed and it is spaced a slight 100

distance away from the adjacent longitudinal edge of the shelf 10, and its lower flange 12 extends inwardly toward the supporting base below the lateral flange 8 thereof. The 5 upper longitudinal surface of the shelf is recessed or grooved by cutting away slightly to provide a seat 13 to receive the upper flange 14 of the retainer and protector strip which is seated in this cut away portion so 10 that its upper surface will be flush with the upper surface of the shelf.

Bolts 15, having tapered heads, are inserted in countersunk openings made in the upper flange 14 of the side strip, and said bolts have 15 a smooth surface upon the greater portion of their shanks so that the threads are provided only upon their lower portions that pass through holes made in the heat insulating strips 9, the lateral flanges 8 of the 20 base and the lower flange 12 of the protecting strips and then pass out below the latter, where the nuts 16 are screwed thereon. The smooth shanks of the bolts 15 pass through smooth bores 17 that are drilled through the 25 edges of the shelf, which bores are greater in diameter than the transverse dimensions of the bolts, so that the latter do not come into contact with the soapstone slabs forming these shelves.

30 It will be seen that practically no portion of the soapstone slab that forms the shelf is in contact with the metal parts of the trays, with the exception of the upper portion where the flange 14 of the securing and protecting strip is seated. It will also be noted that an air pocket 18 is provided between the slab and the web 5 of the base member, and by making the bores 17 larger than the diameters of the bolts any expansion or 40 contraction of the metal parts will be accommodated.

When the trays are traveling through the oven they are side-by-side with their longitudinal edges closely adjacent each other, so as to 45 provide a practically continuous traveler hearth. When the trays reach the end of the oven chamber the rollers engage with large sprockets and the trays will, in traveling around with the sprockets, be disposed at obtuse angles to each other in the manner as 50 shown in Fig. 2, in which position the edges which previously had been closely adjacent each other are now separated to such an extent that the operator may have ready access 55 to the nuts 16 that secure the bolts in position and a new soapstone slab may be readily replaced while the trays are in this position.

It will be obvious that modifications and refinements of the structure herein shown 60 and described may be made without departing from the principles involved. The drawings and detailed description herein are given for the purpose of clearness of understanding only and no unnecessary limitations are 65 to be understood therefrom, but the claims

are to be construed as broadly as permissible in view of the prior art.

A modified structure such as above contemplated is disclosed in Figs. 3 and 4 of the drawings, and by reference to these figures 70 it will be seen that the supporting base for the shelf retains its channel shape in section and there are lateral longitudinal extensions thereon to which the soapstone slab 10 is secured and by which it is supported in spaced 75 relation to the channel-shaped supporting base.

The built-up or composite channel structure illustrated in Figs. 3 and 4 comprises short transverse end-sills 20 that are of angle-metal with the horizontal lateral flanges disposed uppermost, and to these are secured the longitudinal side-sills 21 that are disposed in the same manner and with their horizontal lateral flanges facing each other in the manner shown in Fig. 3 of the drawing. A relatively thinner metal plate 22 is disposed upon the horizontal flanges of the side-sills 21 and completes the channel-shaped composite structure. Plate 22 is of an elongated rectangular shape and, as seen in Fig. 3, it is wider than the composite channel structure so as to provide lateral extensions or flanges 23 along the upper edges of the sides of the channel structure 95 that is similar in function to the flanges 8 of the embodiment disclosed in Figure 1. The heat-insulation strips 9 are placed along the longitudinal edges of the extensions or flanges 23 to receive the soap-stone slab 10 that is assembled on the structure in the same manner as described in connection with the disclosure in Fig. 1, the parts being of the same construction as therein noted and need not be repeated here.

The end-sills 20 are secured to the adjacent links 24 of the traveler-chain intermediate the pivot-pins 25 that connect the rollers 26 thereto and connect the links in longitudinal arrangement as shown in Fig. 4.

What I claim is:—

1. An oven tray comprising a supporting base member, flanges projecting from the sides thereof, a plate supported along its edges upon said flanges, and metal pieces 115 extending along and secured to the edges of said plate and flanges.

2. An oven tray comprising an elongated supporting base member, flanges projecting from the longitudinal positions thereof, a plate supported along its edges upon said flanges, metal pieces extending along the edges of said plate and flanges, and securing means passed through said metal pieces, flanges and the edges of said plate for clamping said parts in assembly on said base.

3. An oven tray comprising a supporting base member of inverted U-shape, flanges projecting laterally from the sides thereof, a plate supported along its edges upon said

flanges, U-shaped metal pieces extending along the top and edges of said plate and under said flange and secured to said parts.

4. An oven tray comprising a channel shaped base disposed with its flanges extended downwardly, flanges projecting laterally from the longitudinal edges of said base at the upper corners thereof, a plate supported along its edges on said flanges, U-shaped protecting strips along the longitudinal edges of said plate with their upper flanges disposed on the top surface of said plate and with their lower flanges engaged with the lateral flanges of said base, and securing means passed through each of said flanges and through said plate for clamping said parts in assembly on said base.

5. An oven tray comprising a channel member disposed with its flanges extended downwardly, flanges projecting laterally from the longitudinal edges of said member at the upper corners thereof, heat insulation strips on said lateral flanges, a plate supported along its edges on said insulation strips, U-shaped protecting strips along the longitudinal edges of said plate with their upper flanges disposed on the top surface of said plate and with their lower flanges engaged with the lateral flanges of said base, and securing means passed through each of said flanges and through said plate for clamping said parts in assembly on said base.

6. An oven tray comprising a channel member disposed with its flanges extended downwardly, angle pieces secured to the upper portions thereof to provide lateral flanges on said channel, a plate supported along its edges on said angle pieces, protecting strips of channel section engaged with said angle pieces and extending over the top of said plate, and securing means passed through the lateral portions of said strips and through said plate and the lateral flanges of said angle pieces.

7. An oven tray comprising a channel member disposed with its flanges extended downwardly, angle-pieces secured to the upper portions thereof to provide lateral flanges on said channel, heat-insulation strips on the upper surfaces of the flanges of said angle-pieces, a plate supported along its edges on said heat-insulation strips, protecting strips of channel-section engaged with said angle pieces and extending over the top of said plate, and securing means passed through the lateral portions of said strips and through said plate and the lateral flanges of said angle-pieces to maintain said plate in assembly with said channel-member.

8. An oven tray comprising a base frame consisting of angle-metal side-rails, angle-metal end-rails connecting the ends thereof, and a flat plate secured to the top of said rails to provide an inverted composite channel, said plate extended beyond the side-rails

to provide longitudinal flanges on said frame, a slab supported along its edges upon said flanges, and metal pieces extending along and secured to the edges of said slab and flanges.

9. An oven tray comprising a base frame 70 consisting of angle-metal side-rails, angle-metal end-rails connecting the ends thereof, and a flat plate secured to the top of said rails to provide an inverted composite channel, said plate extended beyond the side-rails 75 to provide longitudinal flanges on said frame, a slab supported along its edges upon said flanges, metal pieces extending along the edges of said slab and flanges, and securing means passed through said metal pieces, said 80 flanges, and the edges of said slab for clamping said parts in assembly on said base frame.

10. An oven tray comprising a base frame 85 consisting of angle-metal side-rails, angle-metal end-rails connecting the ends thereof, and a flat plate secured to the top of said rails to provide an inverted composite channel, said plate extended beyond the side-rails to provide longitudinal flanges on said 90 frame, a slab supported along its edges upon said flanges, U-shaped metal pieces extending along the top and edges of said slab and under said flanges and secured to said parts.

11. An oven tray comprising a base frame 95 consisting of angle-metal side-rails, angle-metal end-rails connecting the ends thereof, and a flat plate secured to the top of said rails to provide an inverted composite channel, said plate extended beyond the side-rails and providing lateral longitudinal flanges at the upper corners of said frame, a slab supported along its edges on said flanges, U-shaped protecting strips along the longitudinal edges of said slab with their upper flanges disposed on the top surface of said slab and with their 100 lower flanges engaged with the lateral flanges of said base frame, and securing means passed through each of said flanges and through said slab for clamping said parts in assembly upon said base frame. 105
